US00D822506S

(12) United States Design Patent (10) Patent No.: US D822,506 S
(45) Date of Patent:  Jul. 10, 2018

(54) SNACK PACKAGE

- (71) Applicant: Kraft Foods Group Brands LLC,
Northfield, IL (US)
- (72) Inventors: Muluken Tilahun, Waunakee, WI
(US); Paris Alexander Edwards
Lowitz, Chicago, IL (US); Stacy Alycia
Thomas Castro, Chicago, IL (US);
Thad Fisher, Madison, WI (US)
- (73) Assignee: Kraft Foods Group Brands LLC,
Chicago, IL (US)
- () Term: 15 Years
- (21) Appl. No.: 29/571,001
- (22) Filed: Jul. 13, 2016

CLAIM

We claim the ornamental design for a snack package, as shown and described.

DESCRIPTION

FIG. 1 is a front perspective view of a snack package;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken lines in the figures illustrate portions of the snack package and form no part of the claimed design.

1 Claim, 5 Drawing Sheets

See application file for complete search history.
